UNITED STATES PATENT OFFICE.

JAMES A. HORNE, OF ESTES PARK, COLORADO.

READING LAMP.

Application filed May 29, 1926. Serial No. 112,550.

The object of this invention is to provide a simple inexpensive device whereby a book, paper or the like may be illuminated so that a reader may peruse the same without requiring an entire room to be illuminated. The device is especially advantageous in dormitories or other places where a number of persons may be assembled and one of the number may desire to read or work while the others wish to sleep or rest without being disturbed, and a particular object is to provide a device whereby a small lamp may be supported adjacent reading matter or work and will illuminate the same without lighting up the entire room in which it may be located. The invention is illustrated in the accompanying drawing and will be hereinafter fully set forth, the novel features being particularly pointed out in the appended claim.

In the drawing:

Figure 1 is a perspective view of one form of the invention;

Fig. 2 is an enlarged detail section;

Fig. 3 is a detail perspective view showing a lamp-holding element differing in details from the particular lamp-holding element shown in Fig. 1;

Fig. 4 is a detail showing another form of the invention.

In the form of the invention illustrated, there is provided a tubular standard 1 having an open upper end and having an opening adjacent its lower end, the lower extremity 35 of the wall of the tubular standard being compressed and flattened, as shown at 3, to facilitate the application of a clamp thereto. Insulated conductors 4 are inserted through the tubular standard, and these conductors are preferably so treated as to retain the form into which they may be bent at their upper portions, as indicated at 5. The conductors are carried into a socket 6 which may be of any approved detailed construction 40 and is preferably equipped with a reflecting shade 7 of semi-spherical form whereby it will house a lamp 8 in such manner that the light issuing from the lamp will be directed onto a book or work but will be prevented from spreading laterally so that the area illuminated will be confined to the reading space or the space upon which work is to be performed as, for instance, a drawing board. Fitted upon the standard 1 is a bracket 9 55 which, in Fig. 1, is shown as a pair of parallel arms connected by a hub member 10

encircling the standard and held thereto by friction, or permanently, as may be desired, by brazing or otherwise. Between the parallel arms 9 is pivotally secured a lamp-holding arm 11 having a sleeve 12 at its outer end to encircle the socket 6. The flexible but comparatively stiff quality of the upper portion of the conductors will cause the lamp to remain in the position in which it may be set, while the pivotal connection of the arm 11 with the bracket 9 will permit the lamp to be easily adjusted so that the light therefrom will be directed onto the desired area. It will be understood that the arm 11 is frictionally held in its set relation to the bracket 9, and this frictional engagement cooperates with the qualities of the portion 5 of the conductors to maintain the adjustment of the lamp.

Disposed against one side of the lower flattened extremity 3 of the standard is the upper end of a jaw 13 which constitutes the fixed member of a clamp adapted to engage a support, the remaining member or jaw of 80 the clamp, 14, being pivoted to the jaw 13 and normally pressed to the same by a spring 15 coiled around the pivot of the jaws. A set bolt 16 is inserted through the end of the fixed jaw 13 and the flattened extremity 3 of 85 the standard and a set nut 17 is engaged over the end of this screw and turned home against the end of the standard so that, when the nut is turned fully home, the parts will be firmly secured together, although the 90 clasp consisting of the jaws 13 and 14 may be easily turned to any desired position relative to the standard. In many instances, the clamp 13, 14 may be engaged directly with a fixed support as, for instance, the back of a 95 chair, a bed post or other relatively stationary member. It is desirable, however, to provide a more extended support, and to this end I provide the clasp consisting of two jaws 18, 19 pressed together by a spring 20 100 disposed between the shanks 30, 31 of the respective jaws. The jaws 18, 19 are flat and are provided on their opposed faces with protective mats 32 of rubber, felt, corduroy, or other material which will prevent marring of surfaces with which they may be engaged. The jaw 18 is quite wide so as to form an adequate supporting base while the jaw 19 is pivoted between lugs 33 on the lower jaw and is relatively narrow so that it 105 may fit between the jaws 13, 14. The clasp will thus be disposed at a right angle to the

jaws 13 and 14 and may be engaged over the edge of a book or a drawing board so that the lamp will be supported immediately over the book or board.

5 The lamp-holding element illustrated in Fig. 1 is intended more particularly for use where the lamp is to have a more or less permanent relation to the post but it is sometimes desirable to give a wider range 10 of adjustment to the lamp, and, in such instance, the lamp-holding element shown in Fig. 3 may be advantageously employed. In this construction, the member directly engaged with the lamp or the lamp socket comprises the parallel plates 21 connected at one 15 end by a sleeve or hub member 22 adapted to encircle the lamp socket and pivotally attached at their free ends to one member 23 of a clasp which has circular jaws 24 20 adapted to fit around the standard. The movable member 25 of this clasp has one end offset, as shown at 26, whereby it may be easily manipulated, and a spring coiled around the pivotal connection between the 25 two members tends to hold the jaws 24 closed so that they will fit tightly about the standard. This lamp holder may be very easily adjusted to a desired point along the height of the standard or it may be released 30 therefrom and engaged with some stationary object at a convenient point relatively remote from the standard so that the light from the lamp may be directed onto any particular object desired or otherwise most 35 advantageously utilized.

In Fig. 4, the hollow standard 34 is formed at its upper end with a bend or elbow 35 having a convex rib or ball element 36 at its extremity. The socket 37 is fitted at one 40 end about the rib 36, so as to have universal movement thereon, and at its opposite end carries the shade and reflector 38 which corresponds in all respects to the reflector 7. The lamp is engaged in the socket in the 45 usual manner. 39 denotes a clip or pin se-

cured on the standard 34 to permit it to be suspended on a coat or other article of wearing apparel.

It will be understood, of course, that the reading lamp of my invention is to be energized from the usual house current and that a transformer of any known commercial type will be interposed in the feeding conductors 4 so that the current will be reduced to the capacity of the lamp and thereby 50 avoid rapid burning out of the same, it being the purpose of the invention to utilize a very small bulb so that the illumination will be confined to the restricted area desired, such as a drawing, a book or a page of a newspaper or the like. The arrangement illustrated for mounting the lamp upon the standard and for supporting the standard upon a relatively stationary object permits the device to be easily adjusted to meet 55 various conditions and the construction is such that the entire device may be produced at a very low cost.

Having thus described the invention, I claim:

A device for the purpose set forth comprising a tubular standard, means for supporting a lamp on the standard, flexible conductors extending through the standard and connected with the lamp, the lower end of the standard being flattened, a clamp having one member fitted against the flattened end of the standard, a set bolt inserted through the end of said member and the end of the standard whereby to pivotally connect the 70 member to the standard, a nut mounted on the bolt and tightened against the standard, a jaw engaged between and held by the members of the clamp, a second jaw pivoted to said first mentioned jaw, and means for 75 maintaining the jaws in engagement with a relatively stationary object.

In testimony whereof I affix my signature.

JAMES A. HORNE. [L.S.]
